UNITED STATES PATENT OFFICE.

JOHN EDWARD LONG, OF CHILlicothe, OHIO.

COLLAPSIBLE BOLSTER.

SPECIFICATION forming part of Letters Patent No. 655,790, dated August 14, 1900.

Application filed May 16, 1900. Serial No. 16,915. (No model.)

To all whom it may concern:

Be it known that I, JOHN EDWARD LONG, a citizen of the United States, residing at Chillicothe, in the county of Ross and State of Ohio, have invented a new and useful Collapsible Bolster, of which the following is a specification.

This invention relates to collapsible bolsters for beds and the like; and the object of the 10 same is to provide a simple and effective device of a flexible, light, and durable nature for use in dressing a bed and to receive a covering to present a neat external appearance and wherein pillows may be disposed when 15 not in use, the said bolster being reducible to compact form for transportation and storage and constructed of such materials as to render it inexpensive in manufacture and cost to the purchaser.

20 The invention consists in the construction and arrangement of the several parts, which will be more fully hereinafter described and claimed.

In the drawings, Figure 1 is a perspective 25 view of a portion of a bed, showing the improved bolster arranged thereon. Fig. 2 is a perspective view of the improved bolster in reduced form. Fig. 3 is a transverse vertical section of the bolster when rolled.

30 Similar numerals of reference are employed to indicate corresponding parts in the several views.

The numeral 1 designates a thin sheet of light flexible material, preferably tough card- 35 board, to which an exterior protective covering 2 of fabric is secured in any suitable manner, and on the inner portion, adjacent the side edges, wood or other reinforce-strips 3 are attached to brace and strengthen the sheet

40 without materially increasing the weight of the same and also cause the said sheet to regularly shape when rolled into cylindrical form without breaking. The said strips and the sheet at the inner end edges have spring- 45 metal connecting- straps 4 fastened thereto and made longer than the width of the sheet to form an opening 5 when the sheet is rolled and secured in cylindrical form, as clearly shown by Fig. 3. By the provision of the 50 said opening 5 when the bolster is rolled access is permitted to the interior for the inser-

tion and withdrawal of pillows during the day-time or when not desired for use. The free ends of the straps 4 are constructed with keyhole-slots 6 to removably engage headed 55 studs 7 on the outer part of the side edge of the sheet opposite to that from which the said straps project.

When arranged for transportation or storage, the device appears as shown in Fig. 2, 60 and it will be observed that this flat condition of the device permits a large number to be closely packed within a containing receptacle or box. When cylindrically shaped for use on a bed, an outside covering of preferred 65 ornamental or pleasing design is applied thereover, as at 8, and the ends are adapted to be gathered and tied, as shown by Fig. 1, the opening 5 being left clear and the bolster turned to dispose said opening underneath or 70 next to the bed. During the day-time the pillows when not in use will be stored in the bolster, as before explained, and at night or any other time when the service of the pillows is desired the bolster is turned to expose the 75 opening 5 therein, the pillows withdrawn and arranged on the bed in the ordinary manner, and the bolster set or placed to one side. At any time the outer covering of the bolster may be removed and the latter collapsed or 80 reduced to the compact form shown by Fig. 2.

The improved device will be found very convenient to handle both by the manufacturer or shipper and the user, and it will be understood that changes in the form, size, 85 proportions, and minor details can be resorted to without departing from the principle of the invention.

Having thus described the invention, what is claimed as new is—

1. A collapsible bolster comprising a thin sheet of flexible material having holding devices on the outer side edge thereof near the ends, and resilient end straps secured to said sheet and having a length greater than the 95 width of the said sheet, the ends of the straps unengaged by the sheet being provided with articulating devices to removably engage the holding devices on the side edge of the sheet.

2. A collapsible bolster of cylindrical form 100 comprising a thin sheet of flexible material having brace-strips along the side edge por-

tions, resilient metal end straps attached to the sheet and of greater length than the width of said sheet, and having articulating devices in the free ends thereof, and headed studs on the edge of the sheet opposite that from which the straps extend to detachably receive the free ends of the latter.

In testimony that I claim the foregoing as my own I have hereto affixed my signature in the presence of two witnesses.

JOHN EDWARD LONG.
